CART BODY FOR PRESSURE WASHING APPARATUS

Herbert C. Forchemer, 3811 Shasta Drive,
Santa Clara, Calif. 92705

Filed July 3, 1972, Ser. No. 268,488

Term of patent 14 years

Int. Cl. D12—02

U.S. Cl. D12—34

Fig. 1

Fig. 2

Fig. 3

Fig. 4

Fig. 5

FIG. 1 is a perspective view of a cart body for pressure washing apparatus showing my new design.

FIG. 2 is a front elevational view thereof.

FIG. 3 is a right side elevational view thereof.

FIG. 4 is a bottom plan view thereof.

FIG. 5 is a fragmentary cross sectional view thereof and taken along the line 5—5 of FIG. 2.

The broken lines in the drawing are for illustrative purposes only.

I claim:

The ornamental design for a cart body for pressure washing apparatus, substantially as shown and described.
